(57) **CLAIM**

The ornamental design for an automobile, as shown and described.

DESCRIPTION

FIG. 1 is a front perspective view showing our new design for an automobile,

FIG. 2 is a rear perspective view thereof,

FIG. 3 is a front view thereof,

FIG. 4 is a rear view thereof,

FIG. 5 is a top view thereof,

FIG. 6 is a left side view thereof; and,

FIG. 7 is a right side view thereof.

A bottom view is included to aid in an understanding of the other views. The bottom of the present invention does not form part of the claimed design.

1 Claim, 4 Drawing Sheets

FIG. 1

FIG. 2

FIG. 3

FIG. 4

FIG. 5

FIG. 6

FIG. 7
